UNITED STATES PATENT OFFICE

167,670

DAIRY PRODUCTS CARRIER

Clarence H. Berglund, Minneapolis, Minn.

Application April 19, 1952, Serial No. 19,405

Term of patent 14 years

(Cl. D23—1)

To all whom it may concern:

Be it known that I, Clarence H. Berglund, a citizen of the United States, residing at Minneapolis, county of Hennepin, and State of Minnesota, have invented a new, original, and ornamental Design for a Dairy Products Carrier, of which the following is a specification, reference being had to the accompanying drawing, forming part thereof, and in which the single figure is a perspective view of a dairy products carrier, showing my new design.

The characteristic features of the design reside in the solid line portions.

I claim:

The ornamental design for a dairy products carrier, substantially as shown and described.

CLARENCE H. BERGLUND.
